HOUSING FOR A TRANSFORMER OR SIMILAR ARTICLE

John T. Armbruster, Niagara Falls, N.Y., assignor to
American Optical Company, Southbridge, Mass.

Filed Mar. 12, 1962, Ser. No. 69,179

Term of patent 14 years

(Cl. D26—15)

Fig. 1.

Fig. 2.

Fig. 3.

Fig. 4.

FIG. 1 is a perspective view of a housing for a transformer or similar article, showing my new design;

FIG. 2 is a side elevational view thereof;

FIG. 3 is a rear elevational view thereof; and

FIG. 4 is a top plan view thereof.

I claim:

The ornamental design for a housing for a transformer or similar article, substantially as shown.
